UNITED STATES PATENT OFFICE.

HUBERT F. KRANTZ, OF BROOKLYN, NEW YORK, ASSIGNOR TO KRANTZ MANUFACTURING COMPANY INC., OF BROOKLYN, NEW YORK, A CORPORATION OF NEW YORK.

OIL-SWITCHBOARD.

1,272,677.

Specification of Letters Patent.

Patented July 16, 1918.

Application filed May 19, 1913. Serial No. 768,416.

To all whom it may concern:

Be it known that I, HUBERT F. KRANTZ, a citizen of the United States, residing at Brooklyn, in the county of Kings, city and State of New York, have invented certain new and useful Improvements in Oil-Switchboards, of which the following is a clear, full, and exact description.

This invention relates to a switch or panel board, in which the current to be distributed by the board is of such magnitude as to necessitate the breaking of the electrical circuits in a bath of oil or other insulating fluid other than the atmosphere in order to prevent undue arcing of the parts.

It has been before proposed, and often carried out, to break electrical circuits in what is known as an oil switch, which is a switch in which the contacts for the circuit are immersed in oil. It has been the habit and the custom when such switches are to be used on panel boards to mount such oil switch on the board, connect its contacts by strips of copper to the ordinary bus bars of the board, which are located outside of the switch, and to connect the branch circuit wires for distribution to cross bars, in turn connected by strips to the oil switches.

Such oil switches in the above mentioned constructions become in reality an additional burden to be carried by the board to take up room on the board, and to necessitate more electrical joints than would be used in the ordinary construction of a panel board without the oil switch boards.

It is the object of my invention to so mount the bus bars and switch contacts that they will occupy the ordinary operative position on the back board, which they could and would occupy if no oil switches were used, and to incase and inclose the bus bars and switch contacts in an oil bath. I further prefer that an oil bath be maintained across one level of the switch board so that one bath will take in a plurality of switches and one set of bus bars, and this may be carried to such a degree with advantage that across the entire width of board one inclosing tank may be positioned to inclose the bus bars, and switch contacts, and the entire inclosure including the tank mounted directly on the back board, occupying no more space than an ordinary non-oil switch board would occupy, and producing a simple, cheap and comparatively inexpensive and efficient

structure for installation, maintenance and repair.

The scope of my invention will be pointed out in the claims.

In the accompanying drawings:

Figure 1 is a face view of a portion of a panel board equipped with my invention.

Fig. 2 is a section on line 2—2 Fig. 3.

Fig. 3 is a section on line 3—3 Fig. 2.

Fig. 4 is a section on line 4—4 Fig. 3.

As shown in the drawings, the back board 1 is preferably provided with a switch protruding to handles 2 having a shaft 3 passing through the board and carrying a sprocket wheel 4 on its inner end. The handle and sprocket wheel and switch operating mechanism, which I shall describe is only one form which may be used. It is what is known as the slow-break type. I attach to the back plate a tank 5, which may have the let-off cock 6 and to the base of the tank on a suitable insulation 7 I mount parallel one to the other the bus bars 8, which may be plain straight bars or carry lugs 9 for switch contact, such as shown in the drawings.

In the drawings I have shown two of these bus bars 8. In a three-wire circuit it is obvious that there would be three of these instead of two. In the tank 5, I rotatably mount on suitable supports a rod 10 properly insulated by insulating blocks 11 a pair of switch contact blades 12 and 13. I provide a sprocket 14 on the shaft 10 and a sprocket chain 15 connecting the sprocket 14 with the sprocket 4, so that on rotation of the handle 2 the switch contact blades will be rotated to connect directly with the bus bar or the lug 9 thereof, if it is desired to save copper in the construction. The board could be a straight bar without the lugs, as will be obvious. Above each switch contact blade, and adapted to be contacted with it, I carry branch circuit switch contacts 16 mounted in an insulated base 17 permanently secured to the tank by brackets 18, branch circuit connectors 19 being fastened to such additional circuit switch contact blocks. The leading-in wires for power are shown at 20 connected to the bus bar 8, which are bent as shown in Fig. 2 to permit them to pass out of the tank for joinder with the leading-in wire 20.

Besides the advantage secured by this construction as to the oil switch arrange-

ment, it will be noted that the construction shown permits the mounting of both bus bars and branch circuit contacts on supports at right angles to the back plate, so that the 5 switch contact blades may contact directly with such bus and cross bars, and that a clear free plane will be provided between bus and contact blocks of opposite polarity without the crossing of cross bars, an ad- 10 vantage particularly pointed out in several of my co-pending applications for panel and switch boards, particularly that filed September 27th, 1911, No. 651,565, matured into Patent #1,172,371, Feb. 22, 1916.

15 I claim as my invention:

1. An apparatus of the character described, comprising, in combination, a switch board, a covered container secured to one side thereof adapted to be filled with an insulating fluid, a pair of parallel bus bars therein having conductors connected therewith and passing out of said container, a plurality of coacting multipolar means above said bus bars adapted to be connected with 20 conductors leading to a plurality of different conduits, a plurality of individual switching means in said container between said cross bars and said plurality of means for completing the circuit, said switching means co- 25 acting directly with said bus bars, and means without said container on the opposite side on said switch board for actuating said switch means through the cover of said container.
3. A switch - mechanism combining an elongated container; elongated negative and positive bus-bars arranged within a lower region of said container and located in adjacent parallel vertical planes extending 30 lengthwise of said container; a series of negative branch-line terminals all arranged in the plane of the negative bus-bar and located above the same; a series of positive branch-line terminals similarly located in the adjacent plane; a series of switch-blades arranged in said container; and means for individually actuating said blades to establish connection between said terminal and said bus-bars.
5. An oil switch mechanism combining an elongated oil container, a bus bar arranged longitudinally within said container in a position to stand beneath oil which may be contained within the container, means ex-

tending into the container for connecting a 55 conductor to said bus bar, a series of branch line terminals also within the container, said branch line terminals being spaced apart longitudinally of said bus bar and being located in a plane above the bus bar, a series 60 of switch blades also arranged within the container one for each branch line terminal, and means for individually actuating said switch blades to establish connection between the respective branch line terminals and 65 said bus bar.

4. An oil switch mechanism combining a container having imperforate bottom and side walls and being adapted to contain a 70 quantity of oil therein, a bus-bar having a part extending downwardly into said container and having another part extending along the bottom wall of the container adapted to stand beneath the level of oil 75 within the container, a plurality of switch devices spaced apart along the length of the last mentioned portion of the bus-bar, and means extending exteriorly of the container independently operable to cause said switch devices respectively to make and break contact with the bus-bar at will. 80

5. An oil switch mechanism combining a container adapted to contain a quantity of oil, a bus-bar arranged within the container, 85 a plurality of branch-line contacts arranged within the container spaced from the bus-bar and spaced apart along the length of the bus-bar, a pair of insulating plates carried by the container for supporting the bus-bar and the branch-line contacts one adapted to 90 retain the bus-bar in a position beneath the level of oil within the container and the other adapted to support the branch-line contacts in a position in the upper portion of the container, a plurality of switch blades arranged within the container one for each of said branch-line contacts, and means to operate said switch blades for connecting the branch-line contacts respectively with the 95 bus-bar. 100

Signed at Brooklyn, in the county of Kings, city and State of New York, this 16th day of May, 1913.

HUBERT F. KRANTZ.
